UNITED STATES PATENT OFFICE

144,555

DESIGN FOR A BEVERAGE DISPENSER

Louis Gottlieb, Philadelphia, Pa.

Application July 20, 1945, Serial No. 120,825

Term of patent 14 years

(Cl. D2—3)

To all whom it may concern:

Be it known that I, Louis Gottlieb, a citizen of the United States and a resident of Philadelphia, county of Philadelphia, State of Pennsylvania, have invented a new, original, and ornamental Design for Beverage Dispenser, of which the following is a specification, reference being had to the accompanying drawings, forming a part thereof, wherein:

Figure 4 is an end elevational view thereof. The end opposite to the end shown, has substantially the same appearance.

I claim:

The ornamental design for a beverage dispenser, as shown and described.

LOUIS GOTTLIEB.
